UNITED STATES PATENT OFFICE.

JOHN L. BECK, OF SPRINGFIELD, MASSACHUSETTS, ASSIGNOR TO THE AUTO SAFETY CRANK COMPANY, OF HOLYOKE, MASSACHUSETTS, A CORPORATION OF MASSACHUSETTS.

SAFETY CRANKING DEVICE FOR EXPLOSIVE-ENGINES.

1,027,798.

Specification of Letters Patent. Patented May 28, 1912.

Application filed February 24, 1911. Serial No. 610,483.

To all whom it may concern:

Be it known that I, JOHN L. BECK, a citizen of the United States of America, and resident of Springfield, in the county of 5 Hampden and State of Massachusetts, have invented certain new and useful Improvements in Safety Cranking Devices for Explosive-Engines, of which the following is a full, clear, and exact description.

10 An object of this invention is to provide an improved cranking device which in operation is entirely efficient to prevent a back kick when for any reason in the action of cranking the engine shaft takes up a forcible 15 reversed rotation.

Another object is to provide a crank which is always positive and reliable in operation, which in the organization thereof comprises comparatively few, simple, and inexpensively constructed parts. And another object of the invention is to produce a safety crank which is applicable for use with little or no change or addition to established constructions and conditions on any automobile 25 or explosive engine elsewhere used.

The invention is described in conjunction with the accompanying drawings and is defined in the claims.

In the drawings:—Figure 1 is a side elevation of the safety crank as mounted for use in relation to an engine shaft and to a part of a structure in conjunction with which the engine shaft is employed. Fig. 2 is a longitudinal sectional view through the 35 safety cranking device taken substantially on a vertical plane. Fig. 3 is a plan view of the mechanism of the cranking device with certain external parts in central horizontal section. Fig. 4 is a cross sectional view on 40 line 4—4, Fig. 2. Fig. 5 is a cross sectional view as taken on the staggered section line 5—5, Fig. 2. Fig. 6 is a cross sectional view on line 6—6, Fig. 3. Fig. 7 is a perspective view showing in separated relations all of 45 the elemental components of the device.

The cranking device forming the subject of this case is of the same general type as those shown and described in my co-pending applications, Serial Numbers 590,687 and 50 615,676 filed, respectively, November 4, 1910, and March 20, 1911.

In the drawings:—A represents a small portion of the engine shaft having the clutch member A² thereon, as usual.

5 B represents the starting or cranking shaft

having at the rear end thereof the clutch member B² to be thrown by axial movement of the cranking shaft against its spring B³ into engagement with the companion clutch member A² so that by the turning of the 60 crank C in the usual direction the engine shaft may be rotated for cranking up. The cranking shaft B has at its forward end a clutch member comprising parts D and D², the details of construction of which will be 65 hereinafter pointed out. The part D² of the fixed clutch member has the rearwardly facing teeth a. The forward portion of the cranking shaft is made of reduced diameter whereby shoulder b is produced. E represents 70 a sleeve like member having its rearward end abutting against the said shoulder. Said sleeve has an intermediate annular flange e, and its forward end portion is provided with the external screw thread f preferably formed as double or triple threads, and of comparatively massive and strain resisting proportions. The periphery of the sleeve member E to the rear of the shoulder e is made with teeth g as shown in Figs. 2, 3, 6 75 and 7, while its extreme rearward necked down extremity is screw threaded for the reception of the ring nut F thereon. The orifice of the passage at the forward end of the sleeve member is flaring as shown and 80 receives therein the split tapered shell H, the interposition of said shell between the flaring mouth of the sleeve member and the cranking shaft serving to retain the sleeve member in comparatively tight frictional 85 engagement with the shaft.

The starting hand crank C is made at its end with a hollow cylindrical hub C² which incloses the greater portion of the length of the sleeve member E and the clutch member 90 D, D²; on the forward end of the cranking shaft as well also as an annular member G which has its location between the aforementioned flange e and the fixed clutch member. The member G is internally 100 threaded and is in engagement with the threads f of the sleeve member and its forward end is made with teeth h to form a clutch member for coaction with the teeth a of the companion clutch member. The said annular member G, carried in the hollow hub of the crank is normally non-rotative but is axially movable relatively to such hub, and as a provision to this end, said part G is provided with longitudinal peripheral 105

grooves *i* with intervening ribs to receive the engagement therewith of dogs *j* the inwardly projecting ends of which engage in the grooves between the ribs for the establishment of the aforementioned and manifest conditions.

J represents a dust ring screw engaging the rear end of the hub *C*² and forming an internal shoulder for the engagement there-
10 with of the sleeve flange *e*.

L represents a ring encircling the toothed portion *g* of the sleeve member *E* having pawls *h* in engagement with the teeth *g*. This ring is held by the ring nut *F* so that
15 it must move bodily in the axial line of the device as one with the forwardly spring pressed cranking shaft and its equipments, and it is made with a radial extension *L*² which is provided with a bar or dowel *L*³
20 which has a sliding engagement through an aperture *m* therefor in a bracket or fixed part *M* which in practice may be rigidly secured on the front of the automobile frame or suitably otherwise.

25 The cranking shaft is forced into clutch with the engine shaft.

In the cranking operation, the cranking shaft *B* is forced inwardly to engage its clutch member *B*² with the clutch member
30 *A*² on the engine shaft *A* in the usual manner. The crank *C* *C*² is then revolved in the starting direction, or clockwise, *i. e.*, the direction indicated by the arrow in Fig. 5, the engagement of the pawls *j* with the external
35 teeth *i* of the internally threaded annular member *G* causing that member to be moved endwise forwardly into engagement with the teeth *a* of the fixed clutch member *D* *D*² on the outer end of the starting shaft *B*,
40 whereupon said shaft, and, with it, the engine shaft, will be turned.

In case of a back kick, whereby shaft *B* is caused to rotate reversely, (that is, in the direction indicated by the arrow in Fig. 6),
45 the sleeve *E* which is frictionally engaged with said shaft, will be held against backward rotation by the pawls *h* while the shaft itself will now, by reason of the great power exerted by the engine, rotate in a backward direction independently of the sleeve. This backward rotation of shaft *B* and the clutch member *D* *D*² thereon will cause, for an instant, the rotation in a backward direction of the annular internally
50 threaded member *G* which is then in clutch with the said clutch member *D* *D*². When member *G* is rotated backwardly in this manner, it is, also, caused to thread itself inwardly upon and longitudinally of shaft
55 *B*, and further onto the now pawl-held and immovable sleeve *E* so that it will be drawn out of clutch with the fixed clutch member *D* *D*², leaving the backwardly rotating shaft *B* ineffective to communicate any motion to
60 the annular body or crank hub *C*².

It may be explained that on the back kick a slight backward impulse is imparted through the pawl-engaged annular member *G* to the crank in the slight instant required for the annular member *G* to thread itself onto the quick-threaded portion of the sleeve *E* which causes the starting shaft to become unclutched from the crank. This last-explained action transpires so nearly instantaneously that in actual practice a forced backward rotary movement of only about two inches is given at the handle end of the crank; and although this forced movement is transmitted to the hand grasping the crank, the crank throw is ineffective to cause injury to the person employed in the cranking operation.

The spacing collar *t* interposed between the forward end of the tapered friction shell *H* and the inner face of the clutch part *D* acts as a retainer for holding the tapered shell in its effective relation to the sleeve *E*; and the spiral spring *P* is applied, as shown in Fig. 2, in compression between the inner face of the clutch part *D*² and the forward end of the annular internally screw threaded member *G* with the effect of assisting in the releasing emergency action of the device, and is a provision which insures on the "throw out" that the teeth *a* and *h* will not become stripped at their points.

I claim:—

1. The combination with an engine shaft and a cranking shaft adapted to be engaged therewith, of a sleeve normally non-rotative relatively to the cranking shaft mounted on that shaft and frictionally engaged therewith, said sleeve being provided with screw threads, a clutch member fixed on said cranking shaft, a crank having a hub, an annular threaded clutch member located within said hub and connected with the same, said annular clutch member being normally non-rotative but axially movable relative to said hub, and being threaded upon said sleeve, and means operative to permit the rotation of said sleeve with the cranking shaft during the forward rotation of said shaft, but preventing the rotation of said sleeve with said shaft under a reversed back kick rotation thereof.

2. The combination with an engine shaft and a cranking shaft adapted to be engaged therewith, of a sleeve normally non-rotative relatively to the cranking shaft mounted on that shaft and frictionally engaged therewith, said sleeve being provided with external screw threads, a clutch member fixed upon one end of said cranking shaft, a crank having a hub incasing said sleeve, an annular threaded clutch member disposed within said hub, said annular clutch member being normally non-rotative but axially movable relatively to said hub, and being threaded on said sleeve, and means operative to permit

said sleeve to rotate with said cranking shaft during the forward engine-starting rotation of that shaft, but preventing the rotation of said sleeve with said cranking shaft under a reversed rotation thereof.

3. The combination with an engine shaft and a cranking shaft adapted to be engaged therewith, of a sleeve normally non-rotative relatively to the cranking shaft mounted on that shaft and frictionally engaged therewith, said sleeve being provided with external screw threads, a clutch member fixed upon one end of said cranking shaft, a crank provided with a hollow hub incasing said sleeve, an annular clutch member threaded on said sleeve and having external longitudinal ribs and grooves, members carried by the crank hub engaging said ribs and grooves to normally hold said annular clutch member against rotation but permitting axial movement of the same relative to said hub, and pawl-and-ratchet engaging means operative to permit rotation of said sleeve with the cranking shaft during the forward rotation of that shaft, but preventing the rotation of said sleeve with said cranking shaft under a reversed rotation thereof.

4. The combination with an engine shaft and a cranking shaft adapted to be engaged therewith, of a sleeve normally non-rotative relatively to the cranking shaft mounted on that shaft and frictionally engaged therewith, said sleeve being provided with external screw threads, a clutch member fixed on said cranking shaft, a hollow body encircling said sleeve and carrying within it an annular threaded clutch member which is normally non-rotative but axially movable relatively thereto, and which is screw-engaged with said sleeve, a collar encircling said sleeve, pawl-and-ratchet devices coacting between the collar and sleeve, and means operative to prevent revoluble movement of the collar but permitting it to move bodily longitudinally with, and along the axis of, the cranking shaft and relatively to the engine shaft.

5. In a device of the character described, in combination, an engine shaft having a clutch member at its end, and a cranking shaft having adjacent the engine shaft a cooperative clutch member, and having at its forward end another clutch member, a sleeve encircling the cranking shaft and immovable axially relatively thereto, said sleeve having a flaring mouth at one end and having an externally screw threaded portion, a tapered friction shell encircling the cranking shaft, and engaging between said shaft and the flaring mouth of said sleeve to hold the latter normally non-rotative relatively to the cranking shaft, a member encircling said sleeve, an annular clutch member located within said encircling member and normally non-rotative but axially movable relatively

to the same, said annular clutch member being internally threaded for engagement with said sleeve, and pawl-and-ratchet means operative to permit the rotation of the sleeve with said cranking shaft during the forward rotation of that shaft, but preventing the rotation of said sleeve with said cranking shaft under a reversed rotation of the latter.

6. The combination with an engine shaft and a cranking shaft adapted to be engaged therewith, of a sleeve normally non-rotative relatively to the cranking shaft mounted on that shaft and frictionally engaged therewith, said sleeve being provided with external screw threads, a clutch member fixed on said cranking shaft, a crank provided with a hollow hub incasing said sleeve, an annular internally threaded clutch member carried by said hub within its interior, which member is normally non-rotative but axially movable relatively to said hub and is screw-engaged with said sleeve, pawl-and-ratchet engaging means operative to permit the rotation of the sleeve with said cranking shaft during the forward rotation of that shaft, but preventing the rotation of said sleeve with said cranking shaft under a reversed rotation of the latter, and a spring for reaction between the cranking shaft clutch member and the said annular internally threaded clutch member.

7. In a safety cranking device, in combination, an engine shaft and a cranking shaft cooperative therewith, said cranking shaft being provided at its forward end with a fixed clutch member, a sleeve mounted on the cranking shaft and frictionally engaged with the same, and provided with external screw threads, a crank having a hollow hub incasing said sleeve and said fixed clutch member, an annular internally threaded clutch member screw engaging said sleeve, said annular clutch member being normally non-rotative but movable axially relatively to said hub, and means operative to permit forward rotation of said sleeve with said cranking shaft but preventing the rotation of said sleeve with said cranking shaft under a reversed rotation of the latter.

8. In a safety cranking device, in combination, a cranking shaft provided at its forward extremity with a fixed clutch member, a sleeve mounted on the cranking shaft and formed with external screw threads at the forward portion thereof and with a series of peripheral teeth located beyond said threads, means for frictionally engaging the sleeve with the shaft, a crank having a hollow hub incasing said sleeve and fixed clutch member, an internally threaded annular clutch member disposed within said hub in screw engagement with said sleeve, said annular clutch member having a peripheral portion thereof provided with longitudinal grooves, dogs carried by said hub and pro-

jecting into said longitudinal grooves, and a non-revolute ring embracing the toothed portion of said sleeve, and provided with pawls in engagement with such portion.

- 5 9. The combination, with an engine shaft having a clutch member, of a forwardly spring-pressed cranking shaft having a clutch member at its rear end and also provided with a clutch member at its forward 10 end, an externally screw-threaded sleeve mounted on the cranking shaft and provided with peripheral teeth, means for frictionally engaging the sleeve with said cranking shaft, a crank having a hollow hub inclosing 15 said sleeve and the clutch member forward thereof, an internally threaded annular clutch member disposed within said hub in screw engagement with said sleeve, means operative to normally hold the annular 20 clutch member against rotation, but permitting axial movement of the same, relative to said hub, a non-revolute ring embracing the toothed portion of said sleeve member and axially movable bodily in unit 25 son with said sleeve and said cranking shaft, said ring being provided with a bar projecting in a line parallel with the cranking shaft, and a fixed part with which said bar has a sliding engagement.
- 30 10. In a safety cranking device, in combi-

nation, a cranking shaft having a shoulder thereon and provided at its forward end with a fixed clutch member, a sleeve member mounted on the cranking shaft and frictionally engaged therewith, said sleeve abutting at one end against said shoulder and having an intermediate annular flange, the portion of said sleeve forward of said flange being externally screw threaded, a crank having a hollow hub incasing said sleeve, an 40 internally threaded annular clutch member disposed within said hub in screw engagement with said sleeve, said annular clutch member being normally non-rotative but axially movable relatively to said hub, a 45 screw ring engaging the rear end of the hub and forming an internal shoulder for the latter which engages said flange, a non-revolute ring encircling the toothed portion of said sleeve and carrying pawls engaging the 50 teeth of the latter, and a ring nut screw engaging on the rear end portion of said sleeve and disposed against the rear face of said ring.

Signed by me at Springfield, Mass., in 55 presence of two subscribing witnesses.
